UNITED STATES PATENT OFFICE

EDWARD L. BLACKMAN, OF BROOKLYN, NEW YORK

FORE AND AFT RIGGED VESSEL

Application filed August 3, 1931. Serial No. 554,824.

This invention relates to fore and aft rigged vessels in general and more especially to the apparatus for carrying the sails of sail boats, such as sloops, schooners or other like fore and aft rigged vessels.

The subject matter of this application is disclosed in part in my copending application Serial No. 480,888 filed September 10, 1930.

10 Among the objects of the present invention, it is aimed to provide a fore and aft rigged vessel in which the sails are mounted at an angle to the mast so that when the vessel heels with the wind, the sails may be positioned in a plane more nearly at right angles to the thrust of the wind so that the burying effect of the wind is practically overcome or materially reduced.

It is still another object to provide an improved apparatus for mounting the main sail of a fore and aft rigged vessel whereby such main sail may be with facility actuated to assume an angle to the mast so that when the boat heels with the wind, the sail may be positioned in a plane more nearly at right angles to the direction of the wind and thereby be in a position to obtain a maximum efficiency from the propelling force of the wind.

20 It is still another object to provide an improved apparatus for mounting the main sail of a fore and aft rigged vessel so that the main sail may be extended at an angle across the mast and the propelling force on the sail may yet be transmitted substantially centrally of the vessel itself.

It is still another object of the present invention to provide an improved mechanism for mounting a spar on a mast so that the 30 thrust of the wind on the sail may be transmitted more centrally of the vessel.

These and other features, capabilities and advantages of the present invention will appear from the subjoined detail description of specific embodiments thereof illustrated in the accompanying drawings in which

Figure 1 is a perspective showing a fore and aft rigged vessel equipped according to one embodiment of the present invention;

50 Fig. 2 is a plan view of the embodiment

illustrated in Fig. 1 with the sails in full lines arranged similar to the manner illustrated in Fig. 1 and in dotted lines showing the main sail extending outwardly when travelling with the wind;

Fig. 3 is a fragmental enlarged view showing the guide rail along the line 3—3 of Fig. 2;

Fig. 4 is a fragmental enlarged view of the fixture connecting the spar and auxiliary mast to the main mast of the embodiment shown in Fig. 1;

Fig. 5 is a fragmental enlarged section on the line 5—5 of Fig. 4;

Fig. 6 is a fragmental section on the line 6—6 of Fig. 4;

Fig. 7 is a perspective detail showing the claw on the end of the gaff engaging the spar of the embodiment illustrated in Fig. 1.

Fig. 8 is a side elevation of another embodiment of the present invention;

Fig. 9 is a plan view of the embodiment illustrated in Fig. 8;

Fig. 10 is a rear elevation of the embodiment illustrated in Fig. 8;

Fig. 11 is an enlarged section of the spar shown in the embodiment of Fig. 8;

Fig. 12 is an enlarged fragmental view showing the connection of the spar to the sail and mast of the embodiment shown in Fig. 8;

Fig. 13 is an enlarged fragmental view showing the connection of the boom, spar and rail of the embodiment shown in Fig. 8;

Fig. 14 is an enlarged fragmental view of the rail and spar connected thereto of the embodiment shown in Fig. 8;

Fig. 15 is a plan view of a modified guide diagrammatically shown;

Fig. 16 is an enlarged fragmental plan view showing an attachment for automatically controlling the position of the spar and boom on the rail;

Fig. 17 is a section on the line 17—17 of Fig. 16;

Fig. 18 is a section on the line 18—18 of Fig. 17;

Fig. 19 is a plan in detail of another attachment for controlling the position of the boom and spar on the rail; and

Fig. 20 is an enlarged fragmental section on the line 20—20 of Fig. 19.

In the embodiment illustrated in Figs. 1 to 7 inclusive, there is provided a vessel having a hull 1, a main mast 2, a bow sprit 3, an arcuate crossbar 4 near the outer end of the bow sprit 3, a main sheet block traveler 5 near the stern of the vessel, a tiller or helm 6 adjacent to the traveler 5 and four posts 7, 7', 8 and 8' 10 extending upwardly from the deck 1^a of the vessel, the posts 7 and 7' being disposed adjacent to the larboard side of the vessel to one side of the mast 2 and the posts 8, 8' being disposed to extend upwardly from the 15 starboard side of the vessel in alinement with the posts 7, 7'.

Extending from the post 7' to the post 8' abaft the mast 2 and from one side to the other of the vessel, there is formed the I-beam 20 9 which is arcuate in form for the purpose hereinafter to be described.

The left hand end of the I-beam or rail 9 has an extension 10 extending from the post 7' to the post 7, also arcuate in form and the 25 right hand end of the rail or I-beam has an extension 11 extending from the upper end of the post 8' to the upper end of the post 8, also arcuate in form. At the upper end of the main mast 2 and to the front end thereof, 30 there is formed a stepping block 12 which is fixed between the mast 2 and the auxiliary or extension mast 13 by the metallic straps 14 and 15.

The auxiliary or extension mast 13 is preferably only used when an ordinary full length jib is used, such as the jib 16, the upper end of which is connected by the halyard 17 to the pulley 18, which halyard extends down and is connected to the cleat 19 formed on 40 the front face of the main mast 2 adjacent to the deck 1^a.

The rear lower end of the jib 16 is connected by the halyard 20 to the cleat 21 formed on the deck 1^a of the vessel in front of the mast 2. The front lower end of the jib 16 is connected by the halyard 22 to the slide block 23 slidably mounted on the crossbar 4 and connected by the control halyards 24 and 24' to the cleats 25 and 25' formed on the deck 1^a 50 adjacent to the bow of the boat.

At the extreme upper end of the mast 2, there is formed the metallic shell 26 which has formed thereon a pivot pin 27 to receive the collar 28 of the bracket 29, this collar being 55 maintained in pivotal connection with the shell 26 and maintained against displacement by the washer 30 which is anchored and pressed by the nut 31 secured to the upper end of the pin 27.

60 The bracket 29 has formed at its end an enlarged head 32 which is received by the socket 33 at the end of the enlargement 34 formed on the bracket 35 which has formed at its end the metallic shell 36 in which the 65 spar 37 is fixedly mounted in the usual way,

the shell 36 partaking of a barrel-like form with its upper and lower edges alining with and smoothed off to form cam surfaces.

The bracket 35 is pivotally connected to the bracket 29 in that the head 32 is rotatably mounted in the socket 33 and secured in place by the members 38 and 39 secured to the edge of the cup-shaped portion 34 after the head 32 is positioned in the socket 33.

The spar 37 which may partake of any desirable length is preferably formed so that it is secured to the shell 36 at approximately its middle point. The lower end of the spar 37 is preferably pivotally connected to the gripping jaw 40 which engages the upper flange of the I-beam or rail 9 and its extensions 10 and 11 according to the position thereof. The forward end of this gripping jaw 40 is connected to the halyards 41 and 41' which pass under the guide rollers 42 and 42' respectively to the end guide rollers 43 and 43' respectively at the forward ends of the extensions 10 and 11 respectively and then pass back to the block and tackle 44 and 44' respectively, the halyards of which are connected to the cleats 44^a and 44^b respectively adjacent to and in front of the helmsman at the tiller 6. From the foregoing, it will appear that the lower end of the spar 37 may be anchored at any position 95 on the guide 9, a pull on the halyard 41 and a corresponding release on the halyard 41' causing the lower end of the spar 37 to be moved to the larboard side of the vessel and a pull on the halyard 41' and a corresponding release on the halyard 41 causing the lower end of the spar 37 to be moved to the starboard side of the vessel. 100

To the spar 37, there is slidably connected the gaff 45 which is provided at its inner end with two gripping jaws 46 and 47 having cam surfaces 48 and 49 respectively so that when these gripping jaws 46 and 47 come into engagement with the neck 35' of the bracket 35, they will with facility pass the same as indicated in Fig. 6.

Slidably connected to the I-beam 9, there is provided the boom 50 which is attached to the jaw 40 of the spar 37 so that they both slide together upon the I-beam 9. The main sail 51 is secured at its lower edge to the boom 50 in the usual way and at its upper edge to the gaff 45 in the usual way. The sail 51 is also connected to the spar 37. In the present instance, however, the connecting means 52, 53 and 54 which connect the sail to the spar above the shell 36, when the sail is raised completely as shown in Fig. 1 have inner gripping jaw members 55 similar to the jaw members 46 and 47 at the inner end of the gaff 45 so that these connecting members 52, 53 and 54 may pass the neck 35' of the bracket 35 when the main sail is lowered in the act of reefing or furling. 115

The connecting means 56 which connect 120

the main sail to the spar 37 below the shell 36 may be ordinary rings such as have been heretofore so extensively used.

The spar 37 is connected to the main mast 2 by a plurality of graduated rings or loops, in the present instance, three being shown, to with the loops 57, 58 and 59, the upper ring 57 being the smallest in length and size and the lowest ring 59 being the 10 largest in length and size, the smallest ring 57 being long enough so that when the spar 37 is positioned directly in back of the mast 2 with its lower end on the rail 9 directly in back of the mast 2, the distance between the lower end of the spar 37 will be such that the ring 57 may pass down to permit the sail 51 to be lowered to its lowest extent in the act of reefing or furling:

The outer end of the boom 50 is connected 20 by the main sheet block and tackle 60, the lower pulley 61 of which is connected to the traveler 5 and the main sheet or halyard 62 extends back to the cleat 63 directly adjacent to the position of the helmsman at the tiller 6.

25 The gaff 45 is preferably provided with the usual peak halyard 64 which extends from the free end of the gaff 45 to the pulley 65 connected to the upper end of the spar 37 and then passes back to the pulley 66, and then back to the block 65 and then down to the deck in the usual way. The gaff 45 is also provided with the usual throat halyard 67 which extends from the pulley or block 68 down to the block 69 and then back over the block 68 and down to the deck in the usual way.

The embodiment illustrated in Figs. 8 to 13 inclusive is shown as equipped on a fore and aft rigged vessel provided with a Marconi or leg-of-mutton type of rigging and which is provided with a guide rail which merely extends across the deck of the vessel for guiding the spar and is provided with a spar, the connection of which to the mast is such that more than half of the sail area is below the point of attachment, but more than half of the spar is above the point of attachment.

With this embodiment, the thrust of the 50 wind propelling the boat forward is delivered more nearly along the center of the boat and the weight of the longer and heavier upper portion of the spar is thrust more to windward tending to overcome to some extent the pressure of the wind as compared to the embodiment illustrated in Fig. 1. The angle between the spar and mast obtained by the movement of the foot of the spar is increased through putting the point of pivot of the spar 55 below the middle point thereof.

In the present embodiment, the hull 70 is provided with a traveler 71 at the stern, a helm or tiller 72 on the front thereof and a short main mast 73. On the upper end of 60 the short main mast 73 is formed a spreader

74 preferably extending through a bracket 75 as shown in Fig. 8 to which is also connected a top mast 76. The top of the top mast 76 is connected to the ends of the spreader 74 by the stays 77 and 78 and a short distance 70 from the upper end of the top mast 76 there is secured a block or pulley 79 to receive a halyard connected to the upper end of the jib 80, the forward lower end of which is connected by the halyard 81 to the bow of the boat and the rear lower end of which is connected by the block and tackle 82 to the deck of the vessel.

To either side of the main mast 73 and slightly abaft thereof, there are formed the two standards 84 and 85 which support the guide rail 86. The free ends of the spreader 74 are connected by stays 87 and 88 extending down to the deck of the vessel.

The bracket 75 has formed on the rear thereof a pivot pin 89 having an enlarged head 90 to receive the cap 91 of the sleeve 92 in which the spar 93 is rotatably and slidably mounted.

The spar 93 is connected at its lower end 90 to the guide rail 86 and extends up therefrom to and beyond the upper end of the top mast 76 so that the level of the upper end of the main mast 73 will be approximately two-fifths of the distance up to the upper end of the spar 93. Consequently more than half of the spar will extend up above the bracket 75. The upper end of the spar 93 is connected to the upper end of the top mast 76 by a stay 94.

As shown in Fig. 10, the bracket 75 or top of the main mast is connected by the stays 95 and 96 to the standards 84 and 85. The rear of the spar 93 has connected thereto a T-shaped bar 97 having arcuate flanges 98 and 99 extending from the stem thereof to be secured to the spar 93. On the T-shaped bar 97, there are slidably mounted the jaw members 100 having eyes 101 through which extend the loops 102 connected to the main sail 103 in the present instance of the Marconi or leg-of-mutton type.

As will appear from Fig. 12, the flanges 98 and 99 of the T-shaped bar 97 and the stem thereof are cut away adjacent to the sleeve 92 to clear the sleeve 92. The lower end of the spar 93 formed thereon a bracket 104 having an upper cupped shaped portion 105 in which the spar 93 is both rotatably and vertically slidable. The lower end of the bracket 104 is bifurcated having two ears 106 and 107 having alined openings 108 to receive the guide rail 86. Between the ears 106 and 107, there is mounted a double eye member 109 having a vertically extending eye portion 110 and a horizontally extending eye portion 111, the rail 86 extending through the eye portion 110 and the eye 112 extending through the horizontally extending eye portion 111. The eye 112 is secured at the end 113 having a cup shaped por-

tion 114 in which the boom 115 is rotatably secured.

The main sail 103 is connected to the spar 93 by means of the jaw members 100 and 5 connected to the boom 115 in the usual way. The upper end of the main sail 103 is connected by a block 116 to the upper portion of the spar 93 by a halyard not shown. The rear end of the boom 115 is connected by a 10 block and tackle 117 to the traveler 71.

The sides of the bracket 104 are connected by the halyards 118 and 118' which extend across the guide rollers 119 and 120 rotatably mounted on the upper ends of the standards 15 84 and 85, the halyard 118 extending from the roller 119 to the block and tackle 119', the halyard of which is connected to the cleat 119^a adjacent the stern of the vessel as indicated and the halyard 118' extends from the 20 roller 120 to the block and tackle 120', the halyard of which is connected to the cleat 120^a adjacent to the stern of the vessel. From the foregoing, it will appear that the lower end of the spar 93 may be anchored at any 25 position along the rail 86 and that the same will be moved to the larboard side when a pulling force is exercised on the halyard 118 with a corresponding release on the halyard 118' and in turn that the lower end of the 30 spar 93 may be moved to the starboard side of the vessel when a pulling force is exercised on the halyard 118' and the halyard 118 correspondingly released.

To the upper end of the spar 93, there are 35 secured the two stays 121 and 122, the stay 121 extending down to the left side of the spar 93 to the block and tackle 123, the halyard 124 of which extends around the pulley 125 secured to the deck and then has its free 40 end connected to the cleat 125' secured to the deck. The stay 122 is connected to the block and tackle 126 connected to the deck 83, the halyard 127 of which extends around the pulley 128 formed on the deck and then has 45 its free end connected to the cleat 129.

From the foregoing, it will appear that more than half of the spar 93 extends above its connection with the main mast 73 although more than half of the area of the sail 50 103 extends below this connection. In this way, as aforesaid, the weight of the spar would be thrust more to windward overcoming to some extent the force of the wind and the thrust of the wind propelling the boat forward would be delivered more nearly along the center of the boat. Furthermore with this construction a large angle between the spar and mast is obtained by a small movement at the foot of the spar.

In order to facilitate the movement of the 55 spar from side to side of the vessel when tacking or otherwise, the control halyards 118 and 118' are provided. The clearance between the guide rail 86 and the openings in the ears 106 and 107 of the bracket 104 will

be sufficient so that when the sail is swung to one side or other of the spar 93, the spar 93 will be permitted to rotate with it relative to the guide rail 86, it being rotatably mounted in the sleeve 92. 70

In Fig. 14 the guide rail 86 is not shown as formed arcuate, although it could also be so formed, the slideable relation of the spar 93 to the sleeve 92 permitting the lower end of the spar 93 freely to travel from one end to the other of the guide rail 86. 75

In Fig. 15 there is illustrated a modified guide rail which can be used in place of the rail 86. This modified guide rail 130 resembles a double yoke having two arcuate or yoke 80 portions 131 and 132 spaced from one another by the short straight portion 133. The short straight portion 133 is disposed just to the rear of the mast 73 and the arcuate portions 131 and 132 are formed primarily to 85 clear the lower ends of the stays 121' and 122' to take the place of the stays 121 and 122 of the embodiment illustrated in Fig. 8.

The spar 93 is mounted on the guide rail 130 in the same way as the spar 93 is mounted 90 on the guide rail 86 and is provided with a similar pair of halyards 134 and 135 which extend around the idlers 136 and 137 respectively, the halyards 134 extending under the idlers 136 and then around the roller 138 95 at the extreme left hand end of the guide 130 and the halyard 135 passing from the idlers 137 around the roller 139 disposed at the extreme right hand end of the guide rail 130. 100

In Figs. 16, 17 and 18, there is shown an attachment cooperating with the rail, in this embodiment designated as 9^a, for controlling the position and movement of the spar and boom under certain conditions. The rail 9^a 105 is an ordinary I-beam structure curved at its end portions and mounted on the standards 140 and 141 secured to the deck 83^a of the vessel. The spar 142 in this embodiment is connected to a cup shaped bracket 143 having 110 gripping jaws 144 and 145 at its lower end to engage the upper flange of the rail 9^a as illustrated in Fig. 17.

On this cup shaped bracket 143, there is secured a sleeve 146 which is anchored against 115 upward displacement by the collar 147. This sleeve 146 is rotatably mounted on the cup shaped bracket 143 and has formed on its rear end a horizontally extending eye 148 to receive the vertically extending eye 149 120 formed at the front end of the cup shaped bracket 150 to which the front end of the boom 151 is secured.

The lower front end of the bracket 143, see 125 particularly Fig. 18 has secured thereto two spaced apart lugs 152 and 153 which are intended to cooperate with the teeth 154 and 155 formed on the arms 156 and 157 respectively of the control discs 158 and 159 respectively. The discs 158 and 159 normally 130

extend vertically to the deck of the vessel and substantially vertically to the sides of the vessel as indicated in full lines in Fig. 16.

These discs 158 and 159 are provided to extend beyond or above the sides of the vessel so that when the vessel heels to leeward, that is dips to the point where there is danger of capsizing, the disc will come in contact with the water which strikes against it and pushes it backward to the dotted line position shown at the upper portion of Fig. 16 where it will release the bracket 143 whereupon the pressure of the wind on the main sail will cause the boom 151 and spar 142 to slide along the rail 9^a toward the windward side of the vessel.

At the center of the vessel, if desired, there may be formed a stop for determining the movement of the bracket 143 on the rail 9^a when so released. In the present instance, this stop consists of a bifurcated claw 160 pivotally connected to the bracket 161 secured to the vessel centrally thereof. The claw 160 as indicated when swung downwardly will release the rail 9^a and permit the bracket 143 to slide freely from one side to the other of this rail.

On the other hand, when the claw 160 is swung upwardly into engagement with the rail, it will form a stop to determine the movement of the bracket 143 when so released from engagement with the tooth 154 or 155 of the disc 158 or 159 respectively.

On the other hand, when desired, the claw 160 may be swung upwardly into engagement with the rail 9^a after the bracket 143 has been centrally positioned on the rail 9^a when the two fingers of the claw 160 will engage the sides of the bracket 143 and anchor it centrally on said rail 9^a.

The mountings of the arms 156 and 157 are substantially identical and therefore the mounting for the arm 156 illustrated in Fig. 18 will alone be described.

On the deck of the vessel adjacent the starboard side thereof, there is formed the base 162 having a socket 163 extending upwardly therefrom to rotatably receive the plug 164 at the lower end of the bracket 165 having upwardly extending ears 166 between which the arm 156 is pivotally mounted. The starboard side of the socket 163 is provided with a lug 167 extending upwardly therefrom to cooperate with the lower face of the arm 156 to determine the upward movement of the tooth 154. The spring 168 connects the arm 156 with the abutment 169 extending from the socket 163 as indicated normally to urge the arm 156 downward into engagement with the lug 167. The upper end of the socket 163 is provided with a recess 170, the shoulder ends of which form limiting stops for the pin 171 secured to the plug 164 to determine the extent of rotation of the plug 164 and tooth 154 of the arm 156. The extension 172 of the arm

156 on which the tooth 154 is formed is provided with a downwardly extending lug 173 to receive the spring 174 which is connected to the abutment 175 extending rearwardly from the socket 163 normally to urge the arm 156 and disc 158 into the outward position shown in full lines in Fig. 16. When so positioned, the tooth 154 of the arm 156 will be in position to engage the ear 152 at the lower end of the bracket 143.

In operation, if the bracket 143 were moved to the starboard side of the vessel as indicated in Fig. 16 and anchored in position by the tooth 154 and thereupon the vessel would dip to a point where it would be in danger of capsizing and the disc 158 would come in contact with the water, the force of the water on the disc 158 would swing the disc back into the dotted line position shown in Fig. 16 whereupon the tooth 154 would slide off the lug 152 whereupon the wind would cause the spar 142 and boom 151 thereupon to move along the guide 9^a toward the windward side of the vessel, thus relieving the pressure on the sail.

Similarly if the bracket 143 were connected to the tooth 155 of the disc 159 and the larboard side of the vessel dip, the disc 159 would be actuated to release the bracket 143 and permit the wind to swing the main sail and bracket 143 toward the windward side of the vessel.

If in the act of sailing, it were desired to release the bracket 143 from either the tooth 154 or 155 of the discs 158, 159, the same can be swung downwardly out of the path of movement of the lugs 152 or 153 respectively by means of the halyards 176 or 177 respectively which are connected to the arms 156 and 157 respectively and extend downwardly around the pulleys 178 and 179 respectively secured to the deck of the vessel and such halyards then pass rearwardly to the helmsman.

It is of course obvious that the bracket 143 may also be provided with control halyards such as the control halyards 41 and 41' of the embodiment illustrated in Fig. 1 or the control halyards 134 and 135 of the embodiment illustrated in Fig. 15.

In the embodiment illustrated in Figs. 19 and 20, there is provided another arrangement for controlling the movement of the spar and boom along the guide rail. The guide rail in this embodiment is designated as 9^b and likewise is provided with curved end portions and mounted on the standards 140' and 141'.

In the present embodiment, there is provided a rod 180 to the front of the straight portion of the guide 9^b. From the upper ends of the brackets 181 and 182 secured to the lower surface of the guide rail 9^b adjacent to the standards 140' and 141' respectively

120

125

130

on this rod 180, there is freely mounted a coil spring 183.

The rail 9^b in the present instance is also of I-beam construction, the upper flange of which is engaged by the jaw portion 184 of the bracket 185 secured to the lower end of the spar 186, the front end of which jaw 184 is provided with a lug 187 to which is pivotally connected the latch 188 having a recess portion 189 formed in the end thereof to receive the rod 180 when swung into engagement with the same as indicated in Figs. 19 and 20.

The bracket 185 in the present instance is also provided with a sleeve 190 rotatably mounted thereon which is anchored against displacement by the collar 191. This sleeve 190 is provided with an eye 192 to receive the vertically extending eye 193 formed at the end of the cup shaped portion 194 to which the boom 195 is attached.

In operation when the latch 188 engages the rod 180 at the starboard end of the spring 183 as indicated in Fig. 19 with the main sail 15 on the starboard side of the vessel then when an unusual puff of wind is encountered, the same will exercise a force on the main sail to force the boom 195 and spar 186 to the windward side of the vessel along the rail 9^b against the tension of the spring 183. As soon as this unusual puff of wind lets up, the spring 183 will of course move the bracket 185 again to the starboard side of the vessel.

On the other hand, if the latch 188 were 35 positioned to engage the larboard end of the spring 183 and the main sail were extending on the larboard side of the vessel, and an unusual puff of wind were encountered, a force would be exercised on the main sail 25 which would move the boom 195 and spar 186 to the center of the vessel against the tension of the spring 183 and in turn upon the let up of this puff of wind, the spring 183 would again move the bracket 185 to its 40 former larboard position.

The bracket 185 of the present embodiment may also be provided with control halyards such as the halyards 41 and 41' of the embodiment illustrated in Fig. 1.

It is of course obvious that when either the control halyards 41 or 41' of the embodiment illustrated in Fig. 1, or the control halyards 118 or 118' of the embodiment illustrated in Fig. 8, or the control halyards 134 or 135 of 55 the embodiment illustrated in Fig. 15 or the automatic control illustrated in Fig. 16 or the automatic control illustrated in Fig. 19, is used for controlling the lower end of the spar, it will be necessary first to remove or slacken the stays connecting the upper end 60 of the spar to the vessel if not entirely dispense with the same.

It is of course also obvious that by means of the present invention, when it is desired 65 to release the tension of the wind on the sail

by tipping the sail and letting the wind slide over the top, it will only be necessary to allow the lower part of the sail to slide up to windward instead of fastening it down to leeward and thereby the boat may be maintained in its normal substantially vertical position relative to the surface of the water. 70

For example, when sailing into the wind, it is important to have the boat on as even a keel as possible so that its fin keel or centerboard will be as nearly as possible to right angles to the surface of the water and will prevent the sliding of the boat off to leeward. The more the boat heels, the less the effectiveness of the centerboard or fin keel and the 80 more the boat is apt to slide off to leeward. Likewise, when the boat heels, the action of the rudder becomes more downward into the water than sideways, and its effect is more 85 to stop the boat than to steer it.

For both these reasons, a boat sailing into the wind will handle much better and make much better progress on a fairly even keel than when well heeled over. The effect of heeling over is, of course, to release the tension of the wind on the sail by tipping the sail and letting the wind slide over the top. The same result may be obtained by the present invention by merely tipping the sail and allowing the boat to remain in the original 90 position or substantially so, that is as aforesaid by allowing the lower part of the sail to slide up to windward instead of fastening it down to leeward.

It is obvious that various changes and modifications may be made to the details of construction without departing from the general spirit of the invention as set forth in the appended claims. 100

I claim:

1. A fore and aft rigged vessel having a mast, a spar pivotally connected to the upper end of said mast and extending beyond the upper end of said mast, a gaff slidably mounted on said spar to be positioned above the connection between said spar and said mast, a boom pivotally connected to the lower end of said spar, and a sail connected to said spar, gaff and boom. 110

2. A fore and aft rigged vessel having a mast, a bracket on the upper end of said mast, a mast extension secured to said bracket, a spar pivotally connected to said mast, a gaff slidably mounted on said spar, a jib boom on 120 said vessel, a boom pivotally connected to said spar, a jib connected to said mast extension, jib boom and deck, and a main sail connected to said spar, gaff and boom. 115

3. A fore and aft rigged vessel having a 125 mast, a spar pivotally connected at a point below its center to the upper portion of said mast and otherwise free of said mast, a gaff slidably mounted on said spar, a boom pivotally connected to the lower end of said 130

spar, and a sail connected to said spar, gaff and boom.

4. A fore and aft rigged vessel having a mast, a spar pivotally connected to the upper portion of said mast, a gaff slidably mounted on said spar, a boom pivotally connected to the lower end of said spar, a rail extending abaft said mast to which the lower end of said spar is slidably connected, and a sail connected to said spar, gaff and boom.

5. A fore and aft rigged vessel having a mast, a bracket formed on the upper end of said mast, a second bracket pivotally connected to said first bracket, a spar connected to said second bracket, a sail, and connecting means having gripping jaws formed on said sail and gripping said spar, said gripping jaws being slideable past said second bracket when said sail is reefed or furled.

6. A fore and aft rigged vessel having a mast, a guide extending across the deck of the vessel, a spar having its lower end slidably connected to said guide and said spar being pivotally connected to said mast above said guide, a safety device having a lever, and means for releasably connecting the lower end of said spar to said safety device, said safety device being sensitive to the pressure of the water when the vessel dips to submerge the lever of said safety device thereupon to actuate said safety device to release said spar.

7. A fore and aft rigged vessel having a mast, a guide extending across the deck of the vessel, a spar having its lower end slidably connected to said guide and pivotally connected to said mast above said guide, safety devices extending to either side of said vessel, and means for releasably connecting said spar to either of said safety devices, said safety devices being sensitive to the pressure of the water when the vessel dips to submerge either of said safety devices whereupon the pressure of the water will actuate the emerged safety device in turn to release the spar.

8. A fore and aft rigged vessel having a mast, a guide extending across the deck of the vessel, a spar pivotally connected to said mast above said guide and slidably connected at its lower end to said guide, and resilient means for anchoring the spar at either end of said guide and yieldable to permit the movement of said spar toward the center of said guide with an unusual puff of wind.

9. A fore and aft rigged vessel having a mast, a bracket at the upper portion of said mast, a spar connected to said bracket, a gaff, gripping jaws on the end of said gaff slidably engaging said spar to clear said bracket when passing the same, and a sail connected to said spar and gaff.

10. A fore and aft rigged vessel having a mast, a bracket at the upper portion of said mast, a spar secured to said bracket, a gaff, a gripping jaw connecting member at the end of said gaff to slidably receive said spar and

slide past said bracket, a sail connected to said gaff, and gripping jaws formed on said sail and slidably connected to said spar to pass said bracket when said sail is reefed or furled.

11. A fore and after rigged vessel having a mast, a guide extending across the deck of said vessel, a spar pivotally connected to said mast and at its lower end slidably connected to said guide, means for actuating said spar along said guide, a boom slidably mounted on said guide to travel with said spar, and a main sail connected to said spar and boom.

12. A fore and after rigged vessel having a mast, a guide extending across the deck of the vessel, a spar pivotally connected to said mast and at its lower end slidably connected to said guide, and stays connecting the upper end of the spar to the deck of the vessel to either side of the mast, the guide having an inner portion disposed adjacent to the mast and arcuate end portions clearing said stays.

13. A fore and after rigged vessel having a mast, a guide extending across the deck of the vessel, a spar slidably connected at its lower end to said guide and pivotally connected to said mast between its ends, a stay connecting the upper end of said spar with the upper end of said mast, and a main sail connected to said spar.

14. A fore and aft rigged vessel having a main mast, a top mast secured to said main mast, a guide extending across the deck of the vessel, a spar having its lower end slidably connected to said guide and pivotally connected to the upper portion of said main mast between the ends of said spar, a stay connecting the upper end of said spar with the upper end of said top mast, and a main sail attached to said spar.

15. A fore and aft rigged vessel having a mast, a spar pivotally connected to said mast adjacent its center and slidably connected at its lower end to travel across the deck of the vessel, a main sail connected to said spar, removable stays connecting the upper end of said mast to said deck, and removable stays for connecting the upper portion of said spar to said deck.

16. A vessel having a mast, a spar pivotally connected to said mast intermediate the ends of said spar, a sail slidably connected to said spar to be raised or lowered along said spar, a boom attached to the lower edge of said sail, a guide extending across the deck of said vessel aft of said mast, and means associated with said guide, boom and spar to facilitate sliding said boom and lower end of said spar aft of said mast from one side of said vessel to the other.

17. A fore and aft rigged vessel having a mast, a guide extending across the deck of the vessel, a spar pivotally connected to said mast above said guide and slidably con-

nected at its lower end to said guide, and means for anchoring the spar at either end of said guide and yieldable to permit the movement of said spar toward the center of 5 said guide with an unusual puff of wind.

18. A fore and aft rigged vessel having a mast, an upright spar, a sail attached along its luff to said spar, and means to connect said spar pivotally to said mast, said connecting means comprising a double pivot adapted to permit ready transportation of 10 said point of pivotal connection from side to side of said mast, whereby said spar and sail may be shifted bodily to starboard or lar- 15 board as desired without furling the sail or spilling the wind therefrom and may be inclined at any desired angle to the mast.

19. A fore and aft rigged vessel having a mast, an upright spar, a sail attached along 20 its luff to said spar, and means to connect said spar pivotally to said mast, said connecting means comprising a double pivot adapted to permit ready transposition of 25 said point of pivotal connection from side to side of said mast, whereby said spar and sail may be shifted bodily to starboard or

larboard as desired without furling the sail or spilling the wind therefrom and may be inclined at any desired angle to the mast and may be disposed with the foot of the spar, and the attached luff portion of the sail, at 70 a position abaft the mast, or at a position advanced therefrom.

20. A fore and after rigged vessel having a mast, an upright spar, a sail attached along its luff to said spar, and means to connect 75 said spar pivotally, at a point below its center, to said mast, said connecting means including members rotatable upon horizontal and vertical axes, and adapted to permit ready transposition of said point of pivotal 80 connection from side to side of said mast, whereby said spar and sail may be shifted bodily to starboard or larboard as desired without furling the sail or spilling the wind therefrom and may be inclined at any desired angle to the mast, and may be disposed with the foot of the spar, and the attached luff portion of the sail, at a position abaft the mast, or at a position forward of the mast 85 at either side thereof.

EDWARD L. BLACKMAN.
